(57) **CLAIM**

The ornamental design for a tire sidewall, as shown and described.

DESCRIPTION

FIG. 1 is a perspective view of a tire sidewall showing our design;

FIG. 2 is a front elevation view of the tire sidewall of FIG. 1;

FIG. 3 is a rear elevation view of the tire sidewall of FIG. 1;

FIG. 4 is a side elevation view of the tire sidewall of FIG. 1; and,

FIG. 5 is a side elevation view taken from the opposite side of that shown in FIG. 4.

The broken line disclosure in the drawings depicts environmental subject matter forming no part of the claimed design.

1 Claim, 5 Drawing Sheets
